BUILDING CONSTRUCTION

Frederick M. Venzie, Philadelphia, Pa., assignor
to National Gypsum Company, Buffalo, N. Y.,
a corporation of Delaware

Application October 26, 1933, Serial No. 695,239

11 Claims. (Cl. 72—46)

My invention relates to building construction, and, more particularly, to novel interior surfacing units and the assembly thereof to form the interior finished surface of a room or building.

5 The present application is a continuation in part of my co-pending U. S. applications, Serial Nos. 689,579 and 664,703, filed, respectively, September 15, 1933 and April 6, 1933.

10 Heretofore in constructing the interiors of buildings from a multiplicity of units, the units frequently either were so arranged and connected to their supports that a finish coating of plaster was needed to provide an even surface or the construction was not sufficiently fireproof to meet 15 modern building requirements.

The present invention eliminates these faults and comprises the use of a multiplicity of composite units each having a metal surface, adapted to form a portion of a wall or ceiling surface, preferably also with at least two metallic tongued and/or grooved edges to assist in maintaining adjacent units in assembled position, and having a fireproof body of a fireproof material such as gypsum. Such units are connected to metallic 20 supports in such a manner that no portion of the metal of the units comes into contact with the supports, as a result of which the metal cannot act as a conductor of heat and the construction is rendered more fireproof than those structures of the prior art in which the metal face of the surfacing unit is connected by metal with the metallic supports.

An object of my invention is to provide a fireproof building construction in which fireproof surfacing units provided with a smooth surface are positioned to form an interior wall or ceiling surface for a room.

A further object of my invention is to provide surfacing units suitable for use as partition walls, 35 ceiling slabs, or for furring all of which may be formed in a common mold but each of which will best satisfy the requirements of the use to which it is put.

Yet another object of my invention is to provide 40 an interior construction for a building which may be readily and cheaply erected and which will provide a finish at least as smooth and level as that of plaster at less cost.

A more specific object of my invention is to 45 provide an interior construction for a building composed of a multiplicity of fireproof surfacing units, said units being adapted to permit the passage therethrough of means for maintaining the edge of adjacent units in abutting relation-

Other objects and advantages of my invention will be apparent from the following specification, claims, and from the drawings in which:

Fig. 1 is a vertical section through a room embodying my invention;

Fig. 2 is a vertical section showing in detail the connection of a ceiling slab to its support;

Fig. 3 is a vertical section showing in detail the connection of a furring slab to its support;

Figs. 4 and 5 are vertical sectional views showing the connection of a partition unit respectively to its upper and lower supports;

Fig. 6 is a side elevation of one edge of a partition unit;

Fig. 7 is a horizontal section on the line 7—7 of Fig. 1;

Fig. 8 is a horizontal section on the line 8—8 of Fig. 3; and

Fig. 9 is a detailed perspective view of a clip embodied in my invention.

Referring particularly to Fig. 1, from girders or beams 10 forming a portion of the framework of a building are hung a multiplicity of plasterer's channels 11, with their lower faces in a common plane. These form a means for suspending in 25 a common plane uniform ceiling slabs or surfacing units 12 each of which is formed with a plurality of bores 15 therethrough, the axes of which are parallel and lie in a plane parallel to the faces of the units. Through the bores 15 pass 30 tie rods 16 slightly shorter than the width of the units, and threaded at opposite ends 16a to receive a nut 17 whereby adjacent rods are joined (Fig. 8) and adjacent units held with their edges in close abutting relationship under tension, a 35 washer 18 preferably being interposed between the nut 17 and the unit against which it bears. The units 12 are connected to the plasterer's channels 11 by straps 19 passing around the nuts 17 and the channels, as shown most clearly in 40 Fig. 2.

The surfacing units 12 are preferably rectangular in form and formed of fireproof material such as gypsum. They may be made in any suitable mold and prior to their hardening the 45 bores 15 are formed therein by passing rods therethrough temporarily. Preferably the units are formed with notches 13 in their edges adjacent the ends of the bores 15 and re-enforcing rods 14 above the bores, at right angles thereto 50 (Fig. 8), and extending substantially the full length of the unit. Thus when the units are supported by the rods 16 the rods do not depend upon the strength of the gypsum immediately 55 above them for their support but are supported

by the reenforcing rods 14. The gypsum unit after being cured is then placed in a metal shell 30 having tongues 30a and grooves 30b on its edges and secured thereto as by shellac or other suitable adhesive, the metal of the shell extending up the sides of the gypsum past the plane of the bores 15 and being perforated to allow the passage of the rods 16 and nuts 17 therethrough.

- 10 10 In order to support furring or side walls I provide, on the floor F, a nailing strip 25 to which is connected T-shaped clips 26. Into the outer walls W of the building are driven a multiplicity of channel or angle members 20 on which are mounted, preferably by bolts 22, plasterer's channels 21. The channels 21 may be identical with the channels 11 but are positioned so that the surfaces facing the room side lie in a single vertical plane.
- 15 15 20 Surfacing units 12 are positioned on the clips 26, rods 16 passed therethrough, and after the nuts 17 are screwed thereon the units are connected, by straps 19 passing around the nuts 17, to the channel 21. Thereafter other clips 26 are fastened to the nailing strip 25 to hold the room side of the lower end of the surfacing units against the clips 26 previously positioned on the room side thereof.

From the above description it will be obvious that except for the manner in which the lower ends of the surfacing units of the side walls are held in place, and for the difference in planes the ceilings and walls may be of identical construction. It is within the purview of my invention, however, that the thickness of the surfacing units may be varied in accordance with local building laws and that the ceiling surfacing units may be either relatively thicker or thinner than side wall or furring units.

- 30 30 35 40 45 Upon completion of the ceiling and side walls, partitions may be readily erected by positioning angle 24 and nailing strips 25 at desired locations and erecting partition units 35, a U-shaped clip 23 being inserted in slots 33 formed in opposite ends of the units.

The partition units 35 may be made in the same manner as the units 12 but preferably in deeper molds so that they may be thicker, and with a metal shell 30 on each face. Such units preferably are formed with passageways 32 running lengthwise through the units and with the slots 33 in opposite ends through which conduits, etc., indicated at 34, may be run both vertically and horizontally. Since otherwise the partition units 35 are similar to the units 12 previously described and similar numbers have been applied to the parts which they have in common they will not here be further described.

- 50 55 60 65 70 75 Where it is necessary to provide a doorway 36 in a partition wall I prefer to use the doorcase described in detail in my co-pending application for U. S. Patent Serial No. 695,240, filed October 26, 1933. The legs 37 of the doorcase may be of an irregular channel shape in cross section (Fig. 7) and be secured against movement on the floor by clips 38 (Fig. 9). The clips 38 may comprise a rectangular body portion 38a perforated as at 38b and carrying on opposite ends and on one side flanges 38d, 38e, and 38f respectively all at right angles to the plane of the body portion. The same clips may be connected to the leg 37 of the doorcase by bolts 39 carrying the nuts 17 being positioned so as to connect with the rods 16 passing through the units 35. By reason of

this arrangement the units 35 may be held under tension against the doorcase.

In order to finish the end of the walls, either partition or side, the last unit may be sawed lengthwise to the proper dimension and sufficient space left to tighten the nut 17 which should be forced well into the core of the unit. The remaining space may then be filled by an expansion member 40 which comprises two reversed telescoping channels 41 and 42 the larger of the two, 41, being of the same thickness as the walls and lying with its web in contact with the edge of the surfacing unit. The web of the channel 41 is formed with a re-entrant portion 41a the edges of which abut nails 43 or similar projecting means to prevent movement of the expansion unit out of a vertical plane. Expansion springs 44 provide means for keeping the two channels 41 and 42 in extended position and allow the member 40 to be slid over the nail 45 in the wall and the nails 43 in the unit when a compressive force is exerted thereon.

An interior finish constructed as above described provides an even surface which needs only the application of paint to make it ready for use. At the same time the metal shell of the units 12 is maintained out of contact with the tie rods and the straps by which the units are connected to the channels. As a result, in case of fire, heat is not transmitted through these conductors to within the wall but must pass through the relatively non-conductive core.

Various modifications may be made in the above described embodiment of my invention without departing from the spirit and scope thereof, as set forth in the following claims.

What I claim is:

1. A building construction comprising supports, a multiplicity of metal covered fireproof units, means for holding said units with their marginal edges in abutting relationship, and means for connecting said units to said supports.
2. A building interior construction comprising supporting means, a multiplicity of surfacing units, each of said units having a metal face and a fireproof body, the edges of each of said units abutting the edges of adjacent units, and means for connecting said units to said support.
3. A building construction comprising supports, a multiplicity of fireproof units, said units having metal coverings on such faces as are exposed to the room side of said construction, means for holding said units with their marginal edges in abutting relationship, and means for connecting said units to said supports.
4. A building construction comprising supports, a multiplicity of metal covered fireproof surfacing units, means for holding said units with their marginal edges in abutting relationship, some of said units being provided with passageways therethrough in one direction for conduits and in another direction for said last named means, and means connecting said units to said supports.
5. A building interior construction comprising metal supports, a multiplicity of surfacing units each having a metal face and at least two metal edges, and means connecting said units to said supports while maintaining the metal of said units out of contact with said supports.
6. A surfacing unit adapted for erection upon the inside of a building comprising a core of gypsum and a face and at least a portion of two sides of metal, said core having tubular passageways passing therethrough with their axes in

planes parallel to the planes in which lie said metal sides, and bores of lesser diameter than said tubular passageways at right angles thereto, said core being recessed adjacent the ends of said bores.

5. A building interior construction comprising supporting means, a multiplicity of surfacing units adapted for erection upon the inside of a building each comprising a core of gypsum and 10 a face and at least a portion of two sides of metal, at least one of said cores having tubular passageways passing therethrough with their axes in planes parallel to the planes in which lie said metal sides, and bores of lesser diameter than 15 said tubular passageways at right angles thereto, said core being recessed adjacent said bores; tension members passing through said bores for maintaining the edges of adjacent units in abutting relationship, and means engaging said tension members for connecting said units to said 20 supporting means.

8. A building construction comprising a doorcase, surfacing units adapted for assembly to form a wall, means for anchoring said doorcase 25 to a floor, means for connecting said surfacing units to said doorcase, said means necessitating a space between the end of the last of the units

in said wall and an adjacent wall, and an expandible member filling said space and lying in the planes of the major surfaces of said units.

9. A building construction comprising surfacing units, means for connecting each of said surfacing units to an adjacent one to form a wall, said means necessitating a space between the end of the last of the units in said wall and an adjacent wall, and an expandible member filling 10 said space and lying in the planes of the major surfaces of said units.

10. A building construction comprising supports, a multiplicity of surfacing units and expandible means extending the full height of the said units between the end of a wall composed 15 of said surfacing units and a wall at a right angle thereto and lying in the planes of the major surfaces of said units.

11. A building construction comprising supports, a multiplicity of surfacing units, means 20 for connecting said units to form a wall, and expandible means extending the full height of the said units between the end of a wall composed of the said units and a wall at a right angle thereto and lying in the planes of the major surfaces of said units.

FREDERICK M. VENZIE.
